CLAIM

The ornamental design for a file storage cart, as shown and described.

DESCRIPTION

FIG. 1 is a front perspective view of the file storage cart, showing my new design;

FIG. 2 is a rear perspective view thereof;

FIG. 3 is a front elevational view thereof, the rear elevational view is identical;

FIG. 4 is a left side view thereof, the right side view being a mirror image of FIG. 4;

FIG. 5 is a top plan view thereof;

FIG. 6 is a bottom plan view thereof;

FIG. 7 is an enlarged view of detail 7 in FIG. 1;

FIG. 8 is an enlarged view of detail 8 in FIG. 1;

FIG. 9 is an enlarged view of detail 9 in FIG. 1;

FIG. 10 is an enlarged view of detail 10 in FIG. 1;

FIG. 11 is an enlarged view of detail 11 in FIG. 1;

FIG. 12 is an enlarged view of detail 12 in FIG. 1;

FIG. 13 is an enlarged view of detail 13 in FIG. 2;

FIG. 14 is an enlarged view of detail 14 in FIG. 2;

FIG. 15 is an enlarged view of detail 15 in FIG. 2;

FIG. 16 is an enlarged view of detail 16 in FIG. 2;

FIG. 17 is an enlarged view of detail 17 in FIG. 2;

FIG. 18 is an enlarged view of detail 18 in FIG. 2;

FIG. 19 is an enlarged view of detail 19 in FIG. 2; and,

FIG. 20 is an enlarged view of detail 20 in FIG. 2.

The dashed broken lines illustrate portions of the file storage cart which form no part of the claimed design.

The dash-dot-dash broken lines are for notating enlarged views and form no part of the claimed design.
